UNITED STATES PATENT OFFICE.

CLIFFORD E. SCOTT, OF MINNEAPOLIS, MINNESOTA.

DESIGN FOR A HEAT CABINET.

Application filed October 27, 1927. Serial No. 23,911. Term of patent 7 years.

To all whom it may concern:

Be it known that I, CLIFFORD E. SCOTT, a citizen of the United States, residing at Minneapolis, in the county of Hennepin and State of Minnesota, have invented a new, original, and ornamental Design for a Heat Cabinet, of which the following is a specification, reference being had to the accompanying drawing, forming part thereof.

The single view of the drawing is a perspective of a heat cabinet, showing my new design.

I claim:

The ornamental design for a heat cabinet, as shown.

CLIFFORD E. SCOTT.
